CLAIM

The ornamental design for a lighting fixture, as shown and described.

DESCRIPTION

FIG. 1 is a top perspective view of the lighting fixture.

FIG. 2 is a bottom perspective view of the lighting fixture.

FIG. 3 is a front view of the lighting fixture.

FIG. 4 is a right side view of the lighting fixture.

FIG. 5 is a rear view of the lighting fixture.

FIG. 6 is a left side view of the lighting fixture.

FIG. 7 is a bottom view of the lighting fixture; and,

FIG. 8 is a top view of the lighting fixture.

The broken lines in the figures represent features of the lighting fixture that form no part of claimed design.
